UNITED STATES PATENT OFFICE.

WALTER KENNEDY, OF NEW YORK, N. Y., ASSIGNOR, BY MESNE ASSIGNMENTS, TO
KENNEDY-TOOMBS, INC., A CORPORATION OF NEW YORK.

GAS HEATER

Application filed February 16, 1921. Serial No. 445,362.

My invention relates to improvements in gas heaters of the radiant type. According to the present preferred embodiment of my invention, the heater is so designed that it 5 may be converted by interchangeable parts into various forms and designs adapting it to various uses such for instance as where it may be desired to have the heater fit within a recess in a wall, or stand out in the open 10 room with or without a hood and with or without various ornamental features which may be substituted or eliminated as may be found preferable for the particular use for which the heater is intended.

15 Referring to the accompanying drawings, Fig. 1 illustrates in perspective, a suitable type of heater embodying an application of my invention, parts of the same being broken away. Fig. 2 is a transverse vertical section 20 of such a heater. Fig. 3 is an enlarged detail of one of the front legs and columns secured thereupon. Fig. 4 is a similar detail, parts being broken away illustrating the structure and connection of one of the back 25 legs of the heater. Fig. 5 is an enlarged detail illustrating the method of reinforcing or supporting the side tile of the heater. Fig. 6 is a front elevation of one of the ornaments adapted to be secured upon the top of 30 one of the columns. Fig. 7 is a longitudinal section of the same on the line 7-7 of Fig. 6. Fig. 8 is a transverse section, parts being broken away, illustrating the method of securing a canopy upon said heater. Fig. 9 is 35 an enlarged detail in perspective, parts being broken away, illustrating an interchangeable leg structure. Fig. 10 is a cross-sectional detail partly broken away illustrating part of the manifold. Fig. 11 is another similar 40 view of the manifold illustrating the gas supply connected thereto. Fig. 12 is a front elevation illustrating a face plate attachment, for an open hearth. Fig. 13 is a view looking from right to left thereat with the heater 45 attached thereto. Fig. 14 is a perspective view of the canopy illustrated in section in Fig. 8. Fig. 15 is a perspective view, part being broken away illustrating an integral side frame structure. Fig. 16 is a perspective de- 50 tail partly broken away illustrating a modified form of column cap. Fig. 17 is a perspective view partly broken away illustrating an interchangeable column ornament and leg. Fig. 18 is a view looking upwardly at 55 the same, and Fig. 19 is a perspective view

partly broken away illustrating a modification of the leg structure shown in Fig. 9.

Referring now more particularly to Figs. 1, 2, 3 and 4 it will be observed that the front legs 20-20 provide support for the columns 60 22-22' and a base 23 may be secured upon the top of the legs 20-20' by any suitable means such as the screws and bolts 24-25.

26 indicates a depending portion of the frame having flanges such as 27 adapted to 65 be secured to the insides of the legs 20-20' by any suitable means such as the screws 28, thus bridging the legs and columns securely as shown. The hearth frame portion 29 of the heater also extends entirely between 70 the columns above the legs and is secured at the base behind the columns by any suitable means such as the screws 30 and is also provided with a depending flange at the back to which is secured the sheet metal 75 enclosure 32 as shown in Fig. 2 at 35.

The back legs of the heater are indicated by the reference characters 33-33' and these legs are preferably triangular in cross-section and have upwardly extending portions 80 34 through which the screw or bolt 35 projects as shown. The side extensions 36 of these legs pass into the back of the bases of the columns 22-22' where they may be secured by screws such as 37. 85

38 indicates the upper casting or interior frame-work of the heater, the lateral ends of which project forwardly and are secured inside of the front columns by any suitable means such as screws 39, the back of the same 90 being suitably secured to the sheet iron back of the heater 32 by suitable means such as the bolts 40, part of the back being cut away as indicated at 41 to allow for the circulation of air. 95

The main framework of the heater being now secured as above stated, suitable blocks or slabs of refractory or non-combustible material such as indicated by reference character 41' may now be introduced between the channels 42 42' of the upper and lower castings respectively as shown to advantage in Fig. 2 and upon the front or face of these blocks of refractory material, a suitable surfacing of cement or other suitable material 100 may be applied. 105

44 indicates other slabs or blocks of heat radiating material which may be of clay retained between the channels 45-45' also formed in the upper and lower castings re- 110

spectively as shown, the blocks being preferably pitched slightly forward as shown. The so-called upper channel 45 is provided with the projections 46 shown to better advantage in Fig. 1, said projections having depending forward portions 47, and immediately in front of these clay blocks 44 may be secured the grilles 48 which are preferably formed in grille or other artistic formation 10 fire clay or other suitable material. The lower end of the radiant is preferably seated in the removable channel 49 which terminates at opposite ends in enlarged portions 50 which are suitably seated in the base portion 29 as shown. The upper end of the fire clay grille structure or radiant is secured by a fire clay cap such as 51 which is recessed to receive the upper end of the radiant as indicated at 52 and which is recessed at the 15 back to receive the upwardly projecting lugs 53 as shown. 54 are suitable tile members adapted to fit between the back flange 55 of the upper casting and the clay caps 51 previously described.

20 56 are suitable side tiles or blocks preferably cut away at the bottom to clear the ends of the enlarged portion 50 and serve as an inside finish as well as a protection from heat from the radiants. 57 indicates a suitable filler or metallic strap which may be extended downwardly from the side of the top casting as shown to better advantage in Fig. 5 to keep these side tiles snugly in position.

25 58 With the heater now assembled, as above stated, the burners 58 may now be seated upon the frame 29 of the lower casting as shown, the connecting tube 59 thereof coming opposite the plug 60 screwed in the manifold 61 as shown to better advantage in Fig. 10, 62 indicating an adjustable screw needle for regulating the flow of the gas through the plug 60. Also projecting inwardly from the manifold 61 is the female coupling valve 30 63—64—64' adapted to be connected with the gas inlet pipe 65, the same being controlled by the knurled handle 66 as shown in Fig. 11.

35 67 indicates the front tile frame of the heater and is provided with cross members 68 upon which suitable tiles such as 69 may be secured, thus giving a finished appearance to the heater. 70 indicates the top closure formed like an inverted channel with forwardly projecting end portions 71—71' having tongues which pass beneath the caps 73 upon the tops of the columns 22—22', and 74—75 indicate ornaments such as shown in Fig. 6 which may be suitably secured upon the caps 73 by screws such as 76. These ornaments may be provided with an upper portion 75' which may be held upon the base portion 75 by the same screw 76 which penetrates the cap 73 as shown in detail in Fig. 7.

40 65 Instead of using ornaments such as shown in Figs. 6 and 7, a hood or canopy such as shown in Fig. 8 and indicated by the reference character 77 may be employed. In that case another cap 78 may be mounted upon the top 73 and may be secured thereto by any suitable means such as the screw 79 as shown.

45 Where the heater is to be introduced into an opening in a wall such as a fire place, the additional legs such as shown in Fig. 9 may be employed. These may be secured at the sides of the pillars or columns 22—22' as shown in Fig. 1 or may be secured at the front of the same as shown in Fig. 10, thus giving an outward sweep and additional ornamentation as well as additional stability to the heater and adapting it more particularly for inset use as above stated.

50 Referring more particularly to Figs. 12 and 13, it will be observed that as another modification, a face plate such as 80 may be secured in front of the hearth or opening and may be provided with a hood or canopy such as 81. To the back of the face plate, the heater 82 may be secured as shown, extending entirely within the hearth and leaving projecting from the front of the face plate 80, a suitable frame such as 83 and legs 84. When this arrangement is found desirable, the screws 30—39 from the lower and upper castings respectively of the heater as shown in Fig. 2 may be secured in the back of the frame 80 as shown.

55 Fig. 14 shows in perspective an enlarged detail of the canopy shown in Fig. 8. In the modification shown in Fig. 15, the heater is shown provided with the single side frame or casting 85 instead of the legs, columns and sheet metal back such as 20, 22, and 32 of Figs. 1 and 2. In the modification shown in Fig. 16 a cap such as 86 provided with a recess 87 to receive the pin 88 projecting from the top of the column 22 is shown. In the modification shown in Fig. 17 a suitable hollow ornament is illustrated and may be used either for finishing the tops of the column or for the front legs as may be found desirable, and the base portion thereof, illustrated to advantage in Fig. 18, shows a convenient method of securing the same to either the top or bottom of the column. In Fig. 19 the front leg arrangement shown with the cap 89 of Fig. 9 replaced by the ornament 75 which is also shown to advantage in Fig. 6. Also the box-like structure 91 and leg 92 may be separated from the arm 93 and substituted if desired for this purpose. The leg 92 is made with a screw 93 which passes upwardly through the lugs 94—95 extending from the arm 93 and terminates in the base of the ornament 90, the box 91 being cut away at 96 to allow clearance for the lugs 94—95.

60 Referring again to Fig. 11, it will be observed that the coupling valve comprises the

sleeve 64' threaded to receive the gas inlet pipe 65 and rotatably connected by threads or otherwise at the other end to the valve 64 which in turn screws into the manifold at 63 as shown. This connection is more conveniently accessible for connecting up by removing the tile frame 67 but the hand wheel 66 though out of the way is easily accessible for operation without removing the tile frame. The tile frame it will be observed is provided with depending lugs such as 67' to keep it from shifting after it has been placed in position.

Of course it will be understood that various modifications may be made in the construction and arrangement of parts without departing from the spirit of the invention as claimed.

I claim:

1. In a heater of the class described, the combination of refractory slabs between the ends thereof, refractory grilles in front thereof, burners below and between said slabs and grilles, refractory caps for retaining said slabs and grilles in position, and said slabs, grilles, burners and caps forming a composite unit of said heater.

2. In a heater of the class described, the combination of refractory slabs between the ends thereof, refractory grilles in front thereof, and channels across the front of said heater for retaining said grilles and slabs.

3. In a heater of the class described, continuous unit slabs of refractory material pitched slightly forward at the top, grilles of refractory material in front thereof, and burners at the bases and between said slabs and said grilles, said burners individually removable, a manifold at the front of the base of said heater, and tubes connected to said

burners adapted to connect with said manifold.

4. In a heater of the class described, a hearth comprising a forwardly projecting frame, a manifold within the front of said frame, burners adapted to be supported by said frame and connecting with said manifold, and slabs adapted to be supported by said frame over the major part of said burners.

5. In a gas heater, the combination with rear and side walls, of a front frame secured thereto comprising side members and a horizontal front supporting member extending between the side members, a fireback and radiating elements arranged within said walls above said supporting member, a burner arranged and housed within said walls and frame below said supporting plate, there being an opening in said supporting plate, and said front frame side and front members affording access to the burner, and a removable hearth plate constituting a closure for said opening.

6. In a gas heater, the combination with rear and side walls, of a front frame secured thereto comprising side members and a horizontal frame supporting member extending between the side members, a burner arranged and housed within said walls and frame below said supporting member, there being an opening in said supporting plate, and said front frame side and front members affording access to the burner, and a removable hearth plate constituting a closure for said opening.

In testimony whereof I hereunto affix my signature.

WALTER KENNEDY.
